UNITED STATES PATENT OFFICE.

ELMER TOWNSEND, OF BOSTON, MASSACHUSETTS.

IMPROVEMENT IN WIRE FOR SHOE-PEGS.

Specification forming part of Letters Patent No. **88,231**, dated March 23, 1869.

To all whom it may concern:

Be it known that I, ELMER TOWNSEND, of Boston, in the county of Suffolk and State of Massachusetts, have invented a new and useful Threaded Wire; and I do hereby declare the following to be a full and correct description of the same, reference being had to the accompanying drawings, in which—

Figure 1 represents a spool of such wire, and Fig. 2 a detached piece of it.

The nature of this invention consists in raising a spiral thread upon a continuous length of wire by subjecting it to a pressure which alters its form without removing any portion of its substance, and this irrespective of the mode in which wire of this description may be made. I contemplate the use of such wire for the manufacture of screws or pins intended to be driven by percussion instead of by turning, as screws are usually driven.

In order that a threaded pin or screw may be able to turn as it is driven by the blows of a hammer, the line of the thread must be much more oblique to the line of the wire than it is in ordinary screws. Indeed, it would be difficult to cut a screw by the ordinary methods with its thread so much inclined to the line of its length as to adapt it to driving by percussion, or, in other words, to turn as it advanced under the blows of a hammer. Wire of the description invented by me can have the thread raised upon it at any angle to the line of its length that may be required to adapt it perfectly to the mode of driving referred to.

The word "wire" is used in this specification in its ordinary sense to describe a small metallic thread made by drawing.

I wish it also to be understood that the object of this invention is to produce a wire which can be applied to the production of screw-peggs to be used either for machine or hand pegging in the manufacture of boots and shoes. Spools of such wire can be used as waxed thread is used in the thread-pegging machines.

I disclaim the impressing of spiral grooves upon the exterior of rods or tubes for ornamental purposes.

Having thus described my invention, what I claim, and desire to secure by Letters Patent as a new article of manufacture, is—

1. A continuous wire having a spiral thread raised upon it by pressure without the removal of any portion of its substance, as described.

2. Giving to the thread of a continuous wire formed as described such an inclination to the line of the wire as to adapt screws or pins cut from it to be driven by percussion in the direction of their length instead of by turning, as screws are usually driven, substantially as set forth.

The above specification of my said invention signed and witnessed, at Boston, this 29th day of May, A. D. 1868.

ELMER TOWNSEND.
